[57] CLAIM

The ornamental design for a refrigerator, as shown and described.

DESCRIPTION

FIG. 1 is a front, top and left side perspective view of a refrigerator, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an expanded cross-sectional view thereof, taken along line 8—8 in FIG. 2, with the internal system omitted;

FIG. 9 is an expanded cross-sectional view thereof, taken along line 9—9 in FIG. 2, with the internal system omitted;

FIG. 10 is an expanded view of portion 10 in FIG. 8;

FIG. 11 is an expanded view of portion 11 in FIG. 8;

FIG. 12 is an expanded view of portion 12 in FIG. 9; and, FIG. 13 is a front, top and left side perspective view thereof, with drawers pulled out.

The interior structure shown in FIGS. 8 and 9 in phantom lines is for illustrative purposes only and forms no part of the claimed design.

[57] CLAIM

The ornamental design for a refrigerator, as shown and described.

DESCRIPTION

FIG. 1 is a front, top and left side perspective view of a refrigerator, showing our new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof;
FIG. 8 is an expanded cross-sectional view thereof, taken along line 8—8 in FIG. 2, with the internal system omitted;
FIG. 9 is an expanded cross-sectional view thereof, taken along line 9—9 in FIG. 2, with the internal system omitted;
FIG. 10 is an expanded view of portion 10 in FIG. 8;
FIG. 11 is an expanded view of portion 11 in FIG. 8;
FIG. 12 is an expanded view of portion 12 in FIG. 9; and
FIG. 13 is a front, top and left side perspective view thereof, with drawers pulled out.
The interior structure shown in FIGS. 8 and 9 in phantom lines is for illustrative purposes only and forms no part of the claimed design.
